UNITED STATES PATENT OFFICE

108,131

DESIGN FOR A SCRAPING TOOL

Clarence Wheaton Reid, Rochester, N. Y.

Application June 25, 1937, Serial No. 70,058

Term of patent 14 years

To all whom it may concern:

Be it known that I, Clarence Wheaton Reid, a citizen of the United States, residing at 703 Arnett Blvd., in the city of Rochester and in the county of Monroe and State of New York, have invented a new, original, and ornamental Design for a Scraping Tool, of which the following is a specification, reference being had to the accompanying drawings, forming part hereof, wherein—

Fig. 1 is a side elevational view of a scraping tool showing my new design.

Fig. 2 is a front elevational view thereof.

Fig. 3 is a front end elevational view thereof; and

Fig. 4 is a view of the side opposite to that shown in Fig. 2.

I claim:

The ornamental design for a scraping tool, as shown.

CLARENCE WHEATON REID.
